UNITED STATES PATENT OFFICE

2,205,588

ROAD GRADER

Franklin E. Arndt, Galion, Ohio, assignor to The Galion Iron Works & Manufacturing Company, a corporation of Ohio

Application May 12, 1938, Serial No. 207,561

8 Claims. (Cl. 37—156)

This invention relates to a road grader and one of the objects of the invention is to provide a road grader with mechanism such as a mold-board and bank sloper for sloping banks and 5 grading during the same operation, which mold-board and bank sloper can both be adjusted during operation by an operator on the road grader.

A more specific object of the invention is to provide a machine of the above type in which 10 hydraulic means are provided to effect numerous adjustments of the road grader and particularly to effect adjustments of both the moldboard and the bank sloper during operation.

Other objects of the invention will appear 15 hereinafter, the novel features and combinations being set forth in the appended claims.

In the accompanying drawings,

Fig. 1 is a side elevational view of a road grader comprising my invention;

Fig. 2 is a plan view of the grader of Fig. 1;

Fig. 3 is an enlarged perspective view of a portion of the grader illustrating particularly important features of my invention; and

Fig. 4 is a piping diagram of the hydraulic 25 control system preferably employed for adjusting the various elements of the road grader.

Recent developments have indicated a trend 30 toward providing for adjustment of the mold-board of a road grader into a very high or bank sloping position at one side of the grader frame. Road graders of this type have certain very desirable features, yet at the same time they have certain short-comings particularly in that it is 35 impossible to perform simultaneously the operations of grading and bank sloping while forming a ditch between the berm and sloped bank. The road grader of my invention is extremely flexible in operation and is easy to operate particularly in that all of the adjustments of the 40 road grader can be effected by an operator from a station on the grader and more particularly the operator can control the road grader to adjust a moldboard and bank sloper while the machine is in operation to meet varying 45 conditions which may be encountered while the machine is simultaneously grading a road berm and forming a ditch and sloping bank.

By reference to the accompanying drawings, it will be seen that the road grader of my invention comprises structure which to some extent follows the disclosure of and is an improvement over, Patent No. 2,057,039 to Floyd O. De Millar for a Hydraulic road grader, granted October 13, 1936. The road grader of 50 the instant invention comprises a main frame

10 including a pair of spaced apart longitudinally extending channel members 11, 11 which are rigidly attached together intermediate their ends by cross-tubes 12, 12 and at their front ends by cross-plate means 13. Adjacent the cross-plate means 13 at the front end of the main frame 10 there is provided a front steering wheel assembly 14 which performs the function of supporting the front of the main frame 10 and acts to aid the guiding of the road grader. Extending 15 forwardly from the front wheel assembly 14 is a tongue 15 upon which is mounted a pair of reversely connected hydraulic piston motors 16, 16 the pistons of which are connected to the front wheel assembly 14 to aid in the steering of the road grader. The grader as herein disclosed is of the drawn type and will be drawn by a tractor attached to the front end of the tongue 15. If desired, the invention herein disclosed may also be incorporated in a motor 20 grader.

It may also be mentioned that a hydraulic piston motor 17 (see Figs. 3 and 4 of the drawings), is mounted upon the front wheel assembly 14 to effect a leaning of the front wheels 18 of 25 the grader. The rear end of the main frame 10 is supported upon a rear wheel assembly 19 which is laterally shiftable with respect to the main frame 10 by means of a hydraulic piston motor 20, the rear wheels 21, 21 of which are 30 also adapted for leaning by virtue of hydraulic piston motor 22.

Positioned below the main frame 10 and pivotally attached to the front end thereof for universal pivotal movement is a drawbar frame 35 35 which at its rear end is provided with a lateral shift mechanism 24 which in co-operation with a rack 25 carried by the main frame 10, is adapted to shift the drawbar frame 23 laterally to either side of the main frame 10 under the 40 control of the hydraulic piston motor 26. The drawbar frame 23 also carries a circle assembly 27 upon which is mounted a moldboard 28 including a removable blade 29, which moldboard, by virtue of the circle 27, is adjustable with respect to the drawbar frame 23 about an upright 45 pivotal axis 30 by means of rack and pinion means 31 operable by hand wheel 32 adjacent an operator's platform 33 and operator's seat 34. A circle latch mechanism 35 operable by handle 50 36 adjacent the operator's position is provided to maintain the circle in any adjusted position and to release it for adjustment.

The moldboard 28 may be adjusted in elevation and transverse inclination relative to the 55

roadway by means of mechanism comprising extensible hang rods 37 each comprising a rod 37' having a sliding fit in a tube. The lower ends of the rods 37' are connected by ball and socket joints to the opposite sides of the drawbar frame and the upper ends of the tubes are connected by ball and socket joints to the outer ends of the crank arms 38, 38 as shown in Figs. 1 and 2. The rods and tubes have perforations 37" to 10 receive pins for holding the hang rods extended at adjusted lengths.

Reciprocating hydraulic motors are mounted at opposite ends of the rear portion of the vehicle frame with their upper ends connected to 15 the crank arms 40, 40 secured to the rear ends of the longitudinal crank shafts 39, 39, the front ends of which carry the crank arms 38, 38. The crank shafts 39, 39 are journaled on the channel members 11, 11 of the main frame 10, and may 20 be rocked individually by individual operation of the hydraulic motors 41, 42 to lift or lower and angularly adjust the moldboard to a sloping position transversely of the roadway.

Detachably connected to one end portion of 25 the moldboard 28, as indicated at 51' in Fig. 1, is a cutting blade 51 having such a cutting edge contour as to cut a horizontal surface along the bottom of a ditch at one side of the roadway. By means of the laterally shifting mechanism 30 comprising the hydraulic motor 26, the moldboard may be shifted laterally until the bottom cutting edge 51" will be located above the ditch bottom. By means of the drawbar adjusting mechanism comprising the hydraulic motors 41 35 and 42, that end of the moldboard carrying the cutting blade 51 may be lowered into adjusted position so that that portion of the cutting blade 29 shown in Fig. 1 will travel along the berm of the roadway while the lower cutting edges of the 40 cutting blade 51 will effect the desired slope of the adjacent bank of the ditch.

By means of a pivot bolt 43 an auxiliary cutting blade 52 is pivotally connected to the blade 51 as shown in Figs. 1 and 3. The pivot bolt 45 43 is removable so that the auxiliary cutting blade 52 may be detached when it is desired to operate the machine for ordinary road grading purposes only.

Connected to the front side of the upper outer 50 portion of the bank sloper 52 is an extensible pull rod 44. As shown in Fig. 2 the pull rod 44 is pivotally connected at 44' to the bank sloper blade 52 and at 44" to the front end of one of the side members 11 of the main or vehicle 55 frame. The pulling connection 44 preferably comprises a rod telescoping into a tube, the rod and tube being provided with a series of perforations to receive a pin 45 to hold the pulling connection at adjusted length. If desired, the front 60 end of the telescoping connection 44 may be attached to the front end of the drawbar 23 rather than to the front end of the frame 10. The adjustable length of the telescoping connection 44 is adapted to accommodate a wide range of angular positions of adjustment of the moldboard 28 about the upright axis 30. But even after the 65 adjustments are made on the axis 30 and the circle locked in adjusted position relative to the drawbar, the extensible link or pulling connection 44 is also adapted to accommodate a wide range of adjustments of the moldboard effected by the laterally shifting mechanism, and also a wide range of adjustments of the bank sloper blade 52 on its pivot 43 relative to the moldboard 28. It will thus be seen that by removing the 70

pin 45 various adjustments of the moldboard and various adjustments of the bank sloper blade relative to the moldboard may be made after which the pin 45 may be reinserted to hold the connection 44 at adjusted length where it will co-operate with the drawbar in pulling the moldboard and the bank sloper blade 52 while the machine operates during ditch cutting operations. 5

To provide for the adjustment of the bank 10 sloper blade 52 about the pivot afforded by the bolt 43 while the road grader is in operation, and to effect this with a minimum of effort and without requiring the operator to leave his operating station, I provide a hydraulic piston or reciprocating motor 46, the cylinder of which is attached by a ball and socket joint 49 to a bracket 47, carried by the circle 27, as shown in Fig. 3. The bracket 47 is detachably secured by means of the plate 47' and the bolts 47" to the upper 20 end of one of the depending arms 27' which extend rearwardly from the circle, as shown in Fig. 2.

The piston rod end of the hydraulic motor 46 is connected by means of a ball and socket joint 25 48 to the upper end portion of the bank sloper blade 52 at the rear side thereof back of the pivotal connection 44', as shown in Figs. 2 and 3. It will thus be seen that the pivotal connection 49 is located forwardly of a vertical plane extending through the moldboard, the pivot 43 and the bank sloper blade 52, while the pivotal connection 48 is located rearwardly of such vertical plane. This arrangement locates the motor 46 directly above the pivot 43, affords a very 30 firm anchorage at 49 for the rear end of the motor 46, and facilitates operation of the motor 46 in adjusting the bank sloper blade 52 on its pivot 43. As shown in Figs. 1 and 3, the lower end of the blade 52 is located on the front side of the 40 plate 51, and the latter in turn is mounted on the front side of the moldboard 28. During operation of the machine the rearward cutting thrusts of the lower portion of the blade 52 are taken by the plate 51 and the moldboard, while the upper portion of the blade 52 is pulled along a ditch bank by the connection 44. The hydraulic motor 46 may have its piston locked in adjusted position and therefore during operation of the machine while no bending strains are exerted on the motor 46, it is very effective in acting as a strut to resist a backward cutting thrust on the blade 52 during cutting operations thereof. The firm anchorage at 49 and the arrangement of the motor 46 as shown in Fig. 2, are therefore desirable not only for efficiently adjusting the blade 52 relative to the moldboard but also to efficiently co-operate with the pivot 43 in resisting the backward cutting thrusts during bank sloping operations. 55

As clearly shown in Fig. 4, the hydraulic piston motor 46 as well as all of the other hydraulic piston motors on the machine, are of the double acting type, and consequently the piston rods may be positively moved in either direction and 60 locked in any adjusted position.

The extensible pulling connection 44 may be replaced by an extensible hydraulic piston motor similar to the motor 46 but of greater length. Such substituted motor may be provided with a 65 control valve at the operator's station, and controlled to co-operate with the laterally shifting motor 26 and the adjusting motor 46.

As shown in Figs. 1, 2 and 4 of the drawings, 70 all of the hydraulic piston motors are controlled 75

from a plurality of individually operable control valves 116, 117, 120, 122, 126, 141, 142 and 146, all of which are mounted upon a manifold 50 supported from the main frame 10 at the operator's station, such manifold being for the purpose of reducing the piping connections as illustrated in the patent to De Millar, No. 2,057,086, granted October 13, 1936, for an improvement in Controlling apparatus for fluid pressure motors. 5 In other words, all of the control valves as well as the hand wheel 32 and the handle 36 are preferably located at the operator's station or platform 33 adjacent the operator's seat 34. It is thus manifest that all of the adjustments of the road 15 grader are under the control of the operator at a single station at all times and that most of said adjustments can be effected while the road grader is in operation and moving along the roadway. That is to say, while the machine is moving along 20 the roadway during ditching operations, the operator at his station may change not only the adjustment of the moldboard to vary the level of the flat bottom of the ditch, but such operator during movement of the machine may also at any 25 time effect variation of the inclination of the bank sloper 52 relative to the moldboard. This is true notwithstanding the restricting tendencies of the pulling connection 44 because the operator may at any time by pulling on the handle 36 release 30 the latch mechanism 35, thus freeing the circle and moldboard for movement on the upright axis 39 during laterally shifting operations, during adjustments of the transverse inclination of the moldboard, and during angular adjustments 35 of the sloper blade 52 by means of the motor 46. During such release of the circle, the pulling connection 44 holds the moldboard against rotation in a clockwise direction on the axis 39, the tendency of the cutting operations 40 being to move the moldboard in such direction. After the adjustments have been effected from the operator's station, during operation of the machine, the handle 36 may be released, whereupon the latch mechanism 35 will automatically 45 re-connect the circle to the drawbar.

In Fig. 4 the system is shown as including not only the hydraulic piston motors 16, 17, 20, 22, 26, 41, 42 and 46, and the individual control valves therefor 116, 117, 120, 122, 141, 142 and 146 respectively, but also the proper piping connections between each individual control valve and its hydraulic piston motor or motors. In addition, the hydraulic control system includes a pump 53 which is preferably of such construction 55 that fluid under pressure is supplied to the pressure line 54 and full pressure in said line 54 is maintained at all times. The pump 53, however, is so constructed and arranged that whenever no useful work is being done, that is, when no hydraulic piston motor is being operated to effect 60 an adjustment, the volumetric output of the pump 53 will be reduced to substantially zero by automatically operating eccentric ring adjusting mechanism as explained in the above-mentioned 65 Patent No. 2,057,086. Consequently, in the system shown in Fig. 4, fluid under full pressure will be available at any time for immediate action of any of the hydraulic piston motors for effecting any desired adjustment in the machine.

70 Furthermore, each of the control valves, such as control valve 46, is so constructed and arranged that in its normal position, to which it automatically returns when the operating handle is released, the associating piston motor, such as 75 motor 46, will be locked in adjusted position.

This is important particularly in connection with the motor 46 so that it can act as a resisting strut during operation of the bank sloper 52, as hereinbefore explained.

When the operating lever for the valve 146 is 5 moved in one direction, the piston motor 46 will be expanded by positive action and when moved in the opposite direction such piston motor will be contracted by positive action. This is due to the fact that the piston motor 46 is double acting, as is each of the other piston motors shown in Fig. 4.

While I have shown the features of my invention in a pull type road grader, they may be embodied in a self-propelled or motor grader. In 15 the position of adjustment of the moldboard 28 shown in Fig. 3, the machine is adapted to operate to grade the berm at the side of the traveled road surface, such as the hard surface of the road, while the plate 51 will be effective to form 20 the bottom of a ditch, and the bank sloping cutter 52 relied on to properly slope the bank of the ditch at that side thereof remote from the road surface. In this manner, a complete berm 25 grading, ditch forming, and bank sloping operation will be performed by the road grader whether of the pull type or self-propelled type.

Should the operator desire to change the slope of the berm or the slope of the opposite side of the ditch, he may effect such operation without 30 leaving his station because from such station he may control any of the hydraulic piston motors. The motors 41 and 42 may be operated to adjust the slope of the moldboard 28 and to lift and lower it with respect to the main frame 10, and the 35 hydraulic piston motor 46 may be operated to adjust the bank sloper blade 52 relative to the moldboard. It is also evident that lateral adjustment of the moldboard 28 together with the bank 40 sloper blade 52 as a unit, may be effected by 45 means of the adjusting hydraulic piston motor 26 and the mechanism connected between the same and the rear end of the drawbar. This is particularly true if a hydraulic motor is substituted for the pulling connection 44, but even with 50 the latter in place, as shown in Fig. 2, the release of the circle will prevent the pulling connection 44 from interfering with the adjusting operations, and after the operations have been made the circle may be automatically relocked to the drawbar. 55

The hydraulic steering mechanism shown at 14, 16 in Figs. 1 and 2 is described and claimed in my co-pending application Serial No. 18,409, filed April 26, 1935, for an improvement in Road graders, as a division of my co-pending application Serial No. 654,901, filed February 2, 1933, for an improvement in Road graders. In my co-pending application Serial No. 654,901 I have described and claimed the mechanism for adjusting the moldboard in elevation and transverse 60 inclination, such mechanism including the hydraulic reciprocating motors 41, 42 and the laterally shifting mechanism comprising the hydraulic motor 26, the claims in the instant application being directed to improvements and additions not disclosed in either Serial No. 18,409 or Serial No. 654,901. 65

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment 75

ment of my invention, what I desire to secure by Letters Patent of the United States is:

1. In a road grader, the combination with a main frame, of a drawbar attached to said frame, a circle mechanism carried by said drawbar, a moldboard carried by said circle mechanism and adjustable with respect to said drawbar, a bank sloper attached to said moldboard for adjustment relative thereto, power operated means for adjusting said moldboard relative to said frame, and power operated means extending between said circle mechanism and said bank sloper for adjusting said bank sloper relative to said moldboard, both of said power operated means being operable from a single operator's station.
2. In a road grader, the combination with a main frame, of a drawbar frame mounted on said main frame for adjustment relative thereto, a circle mechanism adjustably mounted on said drawbar frame for adjustment about an upright axis, a moldboard carried by said circle mechanism, a bank-sloping cutting blade pivotally connected to said moldboard to occupy a position in angular relation thereto, a fluid-pressure reciprocating motor having one end pivotally connected to said circle mechanism and its other end pivotally connected to the outer end portion of said bank-sloping cutting blade, means for effecting adjustment of said drawbar frame relative to said main frame to adjust the inclination of the moldboard transversely of the path of travel of the machine, and means for effecting the operation of said fluid-pressure reciprocating motor to adjust the bank-sloping cutting blade relative to the moldboard independently of the adjustment of the latter relative to said main frame.
3. In a road grader, the combination with a vehicle frame, of a drawbar flexibly connected at its front end to the front end of said vehicle frame, a circle mounted on the rear end of said drawbar for adjustment relative thereto on an upright axis, a grading blade carried by said circle to move therewith on said upright axis, an auxiliary blade pivotally connected to one end of said grading blade to extend outwardly therefrom at an angle relative thereto, a double acting locking hydraulic reciprocating motor pivotally connected at one end to said circle and at its other end to the outer end portion of said auxiliary blade, means on said frame and connected to opposite sides of the rear end portion of said drawbar to adjust the grading blade to incline downwardly into a ditch at that end thereof carrying the auxiliary blade, means for controlling said hydraulic motor individually to adjust the inclination of the auxiliary blade relatively to the grader blade to slope upwardly from the bottom of the ditch, an extensible pull rod pivotally connected at its front end to said frame and at its rear end to the outer end portion of said auxiliary blade, and releasable mechanism for locking the circle in adjusted position relative to said drawbar, the construction and arrangement being such that during the operation of the machine to cut the opposite bank of the ditch the pull rod co-operates with the drawbar in pulling the blades along the ditch and the hydraulic motor remains locked at adjusted length to serve as a rigid link to rigidly hold the auxiliary blade at its adjusted angle relative to the grading blade.
4. A road grader comprising the combination with a grader blade, of an auxiliary cutting blade pivoted thereto in angular relation therewith, circle mechanism for supporting said grader blade, a fluid pressure motor having one end pivoted to said circle mechanism on one side of a vertical plane extending through the moldboard and said pivot and having its other end pivoted to the rear side of the outer end portion of said auxiliary blade on the other side of such vertical plane, and means for controlling the operation of said motor to effect adjustment of said auxiliary blade on its pivot relative to said grader blade.
5. In a road grader, the combination with a main frame, of a supplemental frame, a moldboard, mechanism comprising a depending arm for supporting said moldboard from said auxiliary frame, a fluid pressure motor, an auxiliary cutting blade pivoted to said moldboard, and means connecting one end of said motor to said auxiliary blade and the other end thereof to the upper end of said arm adjacent the rear end of said supplemental frame.
6. A road grading machine comprising the combination with a drawbar, of a moldboard, mechanism comprising a depending arm for suspending said moldboard from the rear end of said drawbar, an auxiliary cutting blade pivotally connected to one end of said moldboard to occupy an upwardly sloping angular position relative to the moldboard, a hydraulic reciprocating motor, a supporting bracket detachably secured to the upper end of said arm adjacent the rear end of said drawbar, a pivotal connection between said motor and said bracket, a pivotal connection between said motor and said auxiliary blade, and means for controlling said motor to effect adjustment of said auxiliary blade on its pivot relative to said moldboard.
7. In a road grader, the combination with a main frame, of a drawbar frame attached thereto for adjustment, a circle mechanism mounted on the rear end of said drawbar frame for adjustment about an upright axis relative to said drawbar frame, a moldboard mounted on said circle mechanism, an auxiliary blade pivotally mounted at one end of said moldboard, a hydraulic fluid motor of the double acting type attached at reverse ends to the outer end of said auxiliary blade and to said circle mechanism, respectively, for adjusting said auxiliary blade relative to said moldboard and locking it in adjusted position, mechanism operable from a station on said main frame for adjusting said hydraulic motor to adjust said auxiliary blade as aforesaid, and mechanism operable from said station for adjusting the moldboard, auxiliary blade, circle mechanism and rear end of the drawbar as a unit with respect to said main frame.
8. In a road grader, the combination with a main frame having an operator's station thereon, of a drawbar frame pivoted to the front of said main frame, an adjustable circle mechanism carried by the rear end of said drawbar frame, a moldboard attached to said circle mechanism, a bank sloping blade attached to said moldboard for adjustment, power mechanism extending between said circle mechanism and said bank sloping blade to adjust it relative to said moldboard, control means for said power mechanism operable from said operator's station, and means operable from said operator's station for adjusting said drawbar, circle mechanism, moldboard, and bank sloping blade as a unit while said machine is in operation.
